DISPLAY STAND

Melvin W. Custer, Milltown, N.J., assignor to Johnson & Johnson, a corporation of New Jersey

Filed Nov. 30, 1960, Ser. No. 63,038

Term of patent 14 years

(Cl. D80—9)

FIG. 1 is a perspective view of a display stand embodying my new design;

FIG. 2 is a side elevational view thereof;

FIG. 3 is a top plan view thereof; the sign being omitted for convenience of illustration; and

FIG. 4 is an enlarged cross-sectional view thereof taken on line 4—4 of FIG. 2 showing the design of the bottom tray of the display stand.

The dominant features of my design reside in the portions shown in full lines in the drawings.

I claim:

The ornamental design for a display stand, as shown and described.
